VANITY COMPACT

Louis E. Allen, 7401 New Hampshire Ave., Apt. 614,
Hyattsville, Md. 20783

Filed Feb. 25, 1970, Ser. No. 21,623

Term of patent 14 years

Int. Cl. D3—99

U.S. Cl. D86—10

FIG. 1.

FIG. 9.

FIG. 2.

FIG. 4.

FIG. 5.

FIG. 3.

FIG. 6.

FIG. 8.

FIG. 1 is a top plan view of a vanity compact showing my new design;

FIG. 2 is a side elevational view thereof taken on line 2—2 of FIG. 1;

FIG. 3 is a cross-sectional view of part of the latch as viewed substantially on the line 3—3 of FIG. 1;

FIG. 4 is a similar cross-sectional view as viewed substantially on line 4—4 of FIG. 1;

FIG. 5 is a cross-sectional view through the hinge as viewed substantially on line 5—5 of FIG. 1;

FIG. 6 is a bottom plan view thereof;

FIG. 7 is a front elevational view thereof;

FIG. 8 is a rear elevational view thereof; and

FIG. 9 is a front perspective view thereof in an open condition.

The design is characterized by the combination on a generally square compact of laterally spaced opening and clasp members embodying concave upper surfaces disposed in slightly vertically staggered or offset relation and both terminating in generally squared vertical edges; and

with the hinge having adjacently disposed component members having alternately concave surfaces on one side and generally convex surfaces opposite said concave surfaces, and terminating in aligned vertically smooth outer edges.

I claim:

The ornamental design for a vanity compact, substantially as shown and described.
